UNITED STATES PATENT OFFICE.

GEORGE HUNZINGER, OF NEW YORK, N. Y.

IMPROVEMENT IN FOLDING-CHAIRS.

Specification forming part of Letters Patent No. **138,892**, dated May 13, 1873; application filed April 22, 1873.

To all whom it may concern:

Be it known that I, GEORGE HUNZINGER, of the city and State of New York, have invented an Improvement in Folding-Chairs, of which the following is a specification:

This chair is made with cross or **X** legs hinged at the intersection, in combination with a bow connected to the upper ends of the cross-legs and forming the back and arms. The bow is united by slots and pins in such a manner as to fold with the legs, and the bottom is made with a frame hinged near the front to one pair of legs, and resting, when in use, upon a cross-bar between the other pair of legs. This construction is cheap, strong, convenient, and folds easily into a small compass.

In the drawing, Figure 1 is a side view of the chair as folded. Fig. 2 is a vertical section of the chair as open for use, and Fig. 3 is a front elevation.

The legs *a* and *b* are united in pairs by the pivot-bolts or pins *c* at the points of intersection. The bow *d* forms the back and arms of the chair, and it is connected to the upper ends of the cross-legs *a b* and sustains them at the required distance apart when the chair is open, but allows the legs to fold, as in Fig. 1. This is accomplished by slots *i* and pins *o*. The slot is shown in the upper ends of the legs *a*; but it might be in the arms or sides of the bow *d*. The joint *l* unites the upper ends of the legs *b* to the bow *d*. There are cross-bars *f* and *g* to unite the pairs of legs *a a* and *b b* near their lower ends, and the seat

h is united to the cross-bar *k* and swings thereon, and, when turned down into place, said seat rests upon the cross-bar *n*, between the legs *b b*. The back part of the chair may be inclosed by flexible material extending from the bow *d* to the cross-bar *n*. This back may be more or less upholstered or padded, and the seat may also be upholstered or stuffed or closed with elastic material, or caned.

I am aware that the arms of a chair have been hinged to the front of the **X**-legs, and, also, to the sides of the separate hinged back, and that a back with arms has been connected to the front legs in a chair that is not provided with **X**-folding legs.

In my chair the bow forms both back and arms, and, being connected with both the **X**-legs, as set forth, allows of their folding.

I claim as my invention—

1. The bow *d* connecting the top ends of the cross-legs *a b* and forming the back and arms of the chair, as set forth.
2. The flexible material extending from the back *d* to the cross-bar *n*, in combination with the seat *h* connected to the legs *a a* by the cross-bar *k*, and resting, when in use, on said cross-bar *n*, substantially as set forth.

Signed by me this 18th day of April, A. D. 1873.

GEO. HUNZINGER.
